(57) **CLAIM**

The design for the packaging for radio-controlled toy, as shown and described.

DESCRIPTION

FIG. 1 is a perspective view of the packaging for radio-controlled toy showing my new design;

FIG. 2 is a front view thereof;

FIG. 3 is a side view thereof;

FIG. 4 is a rear view thereof;

FIG. 5 is a top view thereof; and,

FIG. 6 is a bottom view thereof.

The broken line illustration of environmental structure in the drawings is not part of the design sought to be patented.
